EZRA CASWELL, OF LYONS, NEW YORK.

Letters Patent No. 75,519, dated March 17, 1868.

IMPROVEMENT FOR BED-BOTTOMS.

The Schedule referred to in these Letters Patent and making part of the same.

TO ALL WHOM IT MAY CONCERN:

Be it known that I, EZRA CASWELL, of Lyons, in the county of Wayne, and State of New York, have invented a new and improved Bed-Bottom; and I do hereby declare that the following is a full, clear, and exact description thereof, which will enable those skilled in the art to make and use the same, reference being had to the accompanying drawings, forming part of this specification, in which—

Figure 1 represents a longitudinal vertical sectional view of my invention.

Figure 2 is a plan or top view of the same.

Figure 3 is a side elevation of the hook that is attached to the frame, and from which the slats are suspended.

Similar letters of reference indicate corresponding parts.

This invention relates to that class of bed-bottoms in which the slats are suspended by means of elastic straps from the side-bars of the bedstead.

The invention consists in the use of a clamp which is secured to the end of the slat, and which has a slotted bar for receiving the ends of the rubber strap, by means of which the slat is suspended. Through the looped end of the strap is fitted a bent rod, the ends of which are fitted over hooks that are secured to the side of the bedstead.

A represents the sides of the bedstead. B B are hooks secured to the same, two hooks being arranged opposite to the end of each slat C. These two hooks may be formed on one plate, a, as shown in fig. 3, or may be secured separate to the bedstead, or one wide hook may be used, extending from end to end of the plate a, as may be desired. To the end of each slat is secured a clamp or frame, D, consisting of one or more pieces of metal or other suitable material. The shape of this clamp is clearly shown in fig. 2. It is a plate, b, solid or perforated, placed upon the slat, having vertical pins, c c, suspended from the sides, which are at their lower ends connected by a strong bar, d, which fits under the slat, and supports the same, as shown. The frame may be tacked to the slat by means of a screw or pin, e, so that it will remain on the slat when the latter is removed from the bedstead. At the end of the frame D, opposite to or near the end of the slat, is formed, on the frame D, a slotted horizontal bar, f, which receives the ends of the elastic strap E, by means of which the slat is suspended from the bedstead. The ends of the strap are clamped in the bar f by means of a wedge, g, which is inserted into the slot of the bar f, as shown in fig. 1, that is, between the ends of the strap or between one end of the strap and one side of the slot. Through the looped end of the strap E is fitted a bent bar, F, the ends of which are bent about parallel to the body, the latter being held in the loop, as shown in fig. 2. The ends of the bar F are fitted over the hooks B, as shown, and thus the slat is suspended from the bedstead.

The manner herein shown and described of securing the ends of the strap in the frame D is far simpler and more economical than any heretofore used. The end of the slat need not be formed in any specific manner, as the frame D, when properly fitted to the slat, forms part of the same, to receive the strap.

I claim as new, and desire to secure by Letters Patent—

The bed-bottom constructed as described, and consisting of the slats C, frame D, having slotted cross-bar f, plate a, having hooks B, link F, elastic strap E, wedge g, and screw e, all arranged and operating as described, and for the purpose specified.

EZRA CASWELL.
